UNITED STATES PATENT OFFICE.

LOUIS P. DISS, OF ILION, NEW YORK, ASSIGNOR TO WYCKOFF, SEAMANS & BENEDICT, OF ILION, NEW YORK, A CORPORATION OF NEW YORK.

TYPE-WRITING MACHINE.

No. 914,123.

Specification of Letters Patent.

Patented March 2, 1909.

Application filed August 5, 1902. Serial No. 118,447.

To all whom it may concern:

Be it known that I, LOUIS P. DISS, a citizen of the United States, and resident of Ilion, in the county of Herkimer and State of New York, have invented certain new and useful Improvements in Type-Writing Machines, of which the following is a specification.

My invention relates to typewriting machines and more particularly to the escapement mechanism thereof; to means for transmitting motion from the finger keys to the escapement mechanism; to means for varying the touch of the finger keys at will without altering the feed action; and to line-lock mechanism.

One of the main objects of my invention is to provide efficient mechanisms of the characters specified and to render the machine as a whole more reliable, rapid and efficient and to these and other ends which will hereinafter appear, my invention consists in the novel construction, arrangements and combinations of parts to be hereinafter described and claimed.

In the accompanying drawings, wherein like reference characters designate corresponding parts in the various views, Figure 1 is a central vertical sectional view of the machine taken from front to rear. Fig. 2 is a rear elevation of the same. Fig. 3 is a plan view of the machine. Fig. 4 is a detail rear elevation of the upper portion of the machine. Fig. 5 is an isolated detail side elevation of a portion of the escapement mechanism and the means for transmitting motion thereto from a finger key. Fig. 6 is a detail rear elevation of the escapement wheel and the back stop pawl or the means for preventing a backward rotation of the escapement wheel when the carriage is moved from left to right. Fig. 7 is a detail plan view of the back stop pawl. Fig. 8 is a plan view of the back stop pawl shown mounted on its support and coöperating with a tooth of the escapement wheel. Fig. 9 is a fragmentary detail plan view, with parts in section, of one member of the line lock mechanism or the so-called arrester. Fig. 10 is a detail end view of the same. Fig. 11 is an enlarged detail perspective view of the feed or stepping dog. Fig. 12 is an enlarged detail side elevation of the feed dogs, the rocker, and an element of the line locking mechanism. Fig. 13 is an enlarged

detail rear elevation of the same. Fig. 14 is an enlarged fragmentary front elevation of the escapement wheel and feed or stepping dog. Figs. 15 and 17 are enlarged detail front elevations of a portion of the means for effecting a change in the touch of the finger keys, the views showing different positions of the parts. Fig. 16 is an enlarged detail plan view of the escapement mechanism and the coöperating mechanism for effecting a change in the touch of the finger keys. Fig. 18 is a side elevation of the feed dogs, the dog carrier and an element of the line lock mechanism, the view being taken in an opposite direction from that of Fig. 12.

The invention is shown in its application to a No. 6 Remington typewriting machine and in the drawings, 1 designates the framing of the machine which is surmounted by the usual top plate 2 and is provided with a fulcrum bar 3 that extends transversely across the machine and coöperates with the notched portions 4 of the key levers 5, each of which is provided at its forward end with a finger key 6. These key levers are restored to normal positions by springs 7 and are guided in their movements by combs 8 and 9. Each of the key levers is connected to a link 10 which in turn is pivoted at its upper end 11 to an arm 12 that extends from a type bar 13, each type bar being pivoted at 14 in a hanger 15 secured to the top plate 2. Extending transversely beneath the various key levers and beneath the key levers 16 of the spacing key or bar 17, is a universal bar 18. This universal bar extends beneath the various key levers near the forward portions thereof and is adjustably connected to upwardly extending links 19 by thumb nuts 20 which are received on the threaded portions 21 of the links. The upper ends of the links 19 are pivotally connected at 22 to crank arms 23 that project from a rock shaft 24 that oscillates or turns in bearings 25 at the forward portion of the machine. This rock shaft extends transversely across the machine from side to side thereof, as illustrated in Fig. 2 and the links 19 are connected to the crank arms on the rock shaft near the ends thereof. A single centrally located crank arm 26 projects downwardly from the rock shaft and is pivotally connected at 27 to a rearwardly extending link 28, the rear end of which is pivoted at 29 to one arm of a bell crank lever 30, pivoted at 31 to a bracket

or hanger 32, that is secured in any suitable manner to the frame 1 of the machine. The other or rearwardly extending arm of the bell crank lever 30 is pivotally connected at 5 33 to an upwardly extending link 34, the upper end of which is pivotally connected at 35 to a crank arm 36 that constitutes a part of one member 37 of the line lock mechanism. This member 37 is apertured and is 10 mounted loosely at its apertured portion upon the rock shaft 38 of the dog rocker, said shaft having coned ends 39 that are adapted to be received within bearings 40 which are in the nature of rods with oppositely disposed recesses in the ends thereof for the reception of the coned ends of the rock shaft. These rods 40 are received in apertures in the lugs 41 which extend rearwardly from the supporting plate or bracket 42 secured to 15 the top plate by screws 43 (see Fig. 1). The bearing rods 40 may be secured in the adjusted positions by screws 44 which are threaded in and extend through threaded openings in the lugs 41.

20 25 Rigidly secured to the rock shaft 38 is a feed dog carrier 45 that is tapped to receive the stem of a screw 46, the stem of this screw 46 extending through an elongated opening 47 in the line locking element 37, and the 30 head of said screw bears upon the side of said element and thus secures the element and dog rocker in the positions to which they may be adjusted relatively one to another. The dog rocker is provided with an offset 35 ear 48 that is tapped at 49 to receive the stem of a screw 50, said stem passing through an aperture in the relatively fixed feed dog 51 so as to rigidly secure the dog 51 to its carrier or dog rocker. When the dog 51 is 40 secured in place the edge 52 thereof abuts against a shoulder or portion 53 on the dog rocker and the fixed dog is prevented from moving relatively to the dog rocker. Laterally extending ears 54 project from the dog 45 rocker and receive between them the loose or stepping dog 55 which is pivoted to the ears at 56. From an examination of Fig. 14, it will be observed that the pivotal center of this loose dog is opposite the beveled portion 50 thereof or is on that side of the dog toward which it moves from the normal or engaged position with a tooth of the escapement wheel to the advanced position where it has to coöperate with the next adjacent tooth of 55 the escapement wheel. In other words, the dog 55 is pivoted to one side of the vertical center thereof, and on that side toward which it moves from the full line to the dotted line position represented in Fig. 14.

60 65 By these means I am enabled to provide a much shorter stepping dog than heretofore with the same or greater efficiency and without liability of the stepping dog moving to a position where it will not extend in the 65 path of the next advancing tooth of the

escapement wheel in the operation of the machine.

It sometimes occurs that the wear on the abutment which limits the movement of the stepping dog toward the advancing tooth of the escapement wheel will permit the dog to be projected to a position where it will not extend into the path of the said advancing tooth. There is little or no liability of this occurring in the present construction and by 70 reason of the peculiar manner of pivoting the feed or stepping dog. This dog is shown in detail in Fig. 11, from which it will be seen that a depending portion 58 extends therefrom and is adapted to abut against the 75 body of the dog rocker to limit the movement of the dog in one direction, as represented in dotted lines in Fig. 14. The movement of the dog in the opposite direction is limited by an abutment 59 on the dog which 80 coöperates with the body portion 60 of the dog rocker, as represented in full lines in Fig. 14. There is also the advantage in the provision of a short stepping dog that a 85 more rapid movement of the parts is provided; the dog being considerably shorter is moved with greater rapidity, notwithstanding the fact that the dog is stronger and more rigid by reason of the decrease in the length thereof. Fig. 14 shows these parts about twice 90 the actual size, whereas Fig. 11 shows the stepping dog about three times the actual size.

From an examination of Fig. 11, it will be seen that the stepping dog is provided opposite its working face with beveled faces 61 100 and 61^x, whereas the fixed dog is provided with beveled working faces 51^a. The bevels 61 and 61^x constitute reentrant bevels which enable the stepping dog to properly clear and avoid conflict with the teeth of the escapement wheel during the movement of the dog rocker back to normal position. The bevel 51^a on the working face of the holding dog affords an advance and quick let-off of the carriage. On reference to Figs. 12 and 110 13, it will be seen that the dog carrier 45 has a laterally extending lug 62 which is tapped to receive the stem of a screw 63 and the stem of this screw passes through openings in the enlarged ends of the leaf springs 64 115 and 65 and the head of the screw bearing on these springs securely unites the ends thereof to the dog rocker. These springs are likewise provided with enlargements 66 which have central perforations 67 therein to permit the rock shaft 38 to extend freely there-through. The spring 64 is shorter than the spring 65 and the upper end of the spring 65 is bent at right angles to its body portion at 68 and projects through an opening 69 in the 120 dog rocker, the free end of the spring bearing on the feed dog 55 and within the recessed portion 70 thereof so that the tension of both springs is exerted to force the stepping dog from the full line position to the dotted line 125 130

position represented in Fig. 14. By the employment of the two leaf springs as shown, I am enabled to provide a flexible and reliable spring structure without the liability 5 of the springs being broken, a difficulty which has presented itself heretofore in the employment of a single comparatively stiff spring. The dog rocker 45 is tapped transversely for the reception of a screw stop 71 which extends therethrough and is adapted 10 to coöperate with an abutment 72 that is in the nature of a plate secured to a lug 72^x that extends from the bracket-like plate 42 (see Fig. 12). The screw-stop 71 and abutment 72 limit the throw of the dog rocker and the parts connected thereto in the forward movement thereof and also limit the 15 downward movement of the universal bar connected with the dog rocker. The locking element 37 is provided with a laterally extending ear 73 (see Fig. 5) which is tapped transversely to receive a screw-stop 74 that extends therethrough and the forward end of which is adapted to bear upon a shoulder or lug 75 which projects from the dog rocker 45 so that when the screw 46 is loosened the screw stop 74 may be turned to afford an 20 adjustment of the line locking element 37 and the dog carrier relatively one to the other, after which the screw 46 may be tightened and the parts secured in the adjusted position. The lug 75 hereinbefore referred to, has projecting from its forward face a pin 76 which projects into an opening 25 that extends through one end of the bow or leaf spring 77, the opposite end of this spring being rigidly secured to the bracket plate 42 by a screw 78. The spring is likewise apertured intermediate of its ends for the free 30 passage of the stem of a screw 79 which is received within a threaded opening in the bracket plate and the head of this screw 79 bears upon the spring and affords a means for adjusting the tension thereof. The tension 35 of this spring 77 is exerted upon the dog rocker and tends to force it towards the rear of the machine around its pivotal center. By the employment of a spring 77 of the character shown I am enabled to secure an 40 easier and more resilient or elastic action than with the coiled torsional spring heretofore in common use.

The arm 36 of the line locking element is provided with a bearing shoulder 80 in the path of which an arm 81 of a bell crank lever 82 extends. This bell crank lever is pivoted at 83 to the bracket plate 42 and the arm 81 constitutes a stop to limit the movement of the arm 36 in one direction and consequently 45 to limit the movement of the dog rocker, the abutment 84 of the line locking element and the universal bar back to normal position, as will hereinafter more clearly appear. This bell crank lever 82 is provided with a depend- 50 ing arm 85 which has a disk-like weight 86

rigidly secured to the end thereof, said weight being so positioned that when the arm 81 is slightly elevated the weight moves substantially horizontally, so that said weight opposes such motion by its inertia 70 only, and not by its gravity. The inertia of the weight is substantially equal to that of the dog rocker. The arm 81 or the lever 82 is connected at 87 to one end of a coiled contractile spring 88, the lower end of this spring 75 being connected at 89 to an arm 90 that projects from a stem 91 that is seated in a bearing within a lug 92 (see Figs. 1, 2 and 4) and is adapted to turn therein, in order to adjust the tension on the spring 88. The stem 90 and arm 80 89 may be secured in the adjusted position by a set screw 93 the stem of which is received within a threaded opening in a lug 92 and bears at its inner end against the stem 91.

The free end of the arm 81 is adapted to 85 rest upon a stop 94 which is in the nature of a plunger that is movable longitudinally and is provided at its lower end with a knurled head 95. This plunger is received and adapted to move longitudinally in a central 90 opening that extends through the exteriorly threaded sleeve 96, whereas the sleeve may be adjusted vertically in the threaded opening in the lug 97 in which it is received, the lug projecting from the front face of the 95 plate or bracket 42. A nut-like head 98 is formed on the screw sleeve to facilitate this adjustment of the sleeve and an expansion spring 99 surrounds the plunger and is interposed between the knurled head 95 and the 100 nut-like head 98, on the sleeve so that the spring exerts a downward tension on the plunger stop 94. This plunger stop is provided near its upper end with laterally extending pins 100 which are adapted to be received within half-round apertures 101 in the upper edge of the sleeve 96, as shown in Fig. 15. By slightly raising the stop 94 the pins 100 may be withdrawn from the seats or apertures in which they rest and a partial turn 110 of the stop, with the aid of the knurled head 95, will bring the pins opposite the inclined or cam-like portions 102 on the upper end of the sleeve 96. If the knurled head be released at this time the spring 99 will tend to force 115 the stop 94 to the lowermost position represented in Fig. 17, where the pins 100 will be seated within recesses 101 that correspond to those at the highest portion of the sleeve and the stop will be prevented from accidental 120 displacement. A vertical adjustment of the sleeve 96 will vary the height of the stop 94 whether the latter be in the highest or the lowest position to which it may be set in the sleeve 96. The purpose of this adjustment 125 will hereinafter more clearly appear. The part 82 is provided with an upwardly extending arm 103 and at the upper end of this arm is an interiorly threaded sleeve 104 which receives a screw-stop or abutment 105 that 130

may be adjusted in the sleeve 104 for purposes which will hereinafter appear.

The feed dogs 51 and 55 coöperate with the teeth of an escapement wheel 106 that is operatively connected to a shaft 107 through the intermediate pawls (not shown) in the usual manner. This shaft 107 carries a feed pinion 108 at its forward end for coöperation with a feed rack 109 that is connected to arms 110 pivoted at 111 to the carriage 112. The carriage may be of the ordinary construction and is provided with rollers 113 that bear upon a transverse rail 114 and a front roller 115 which bears upon the shift rod 116. The usual platen 117 may be provided together with the guide rail 118. A stop 119 of the usual or any preferred construction is carried by the carriage and co-operates with an adjustable stop 120 carried by the rack or stop bar 121 that is mounted upon pins 122 and is adapted to receive a slight turning as well as a longitudinal movement and to travel for a limited distance with the carriage against the tension of the spring 123, as in the No. 6 Remington machine. To the underside of this rack 121 is secured by screws 124 a bracket 125 that carries at its extremity a housing 126 in which a so-called arrester 127 is adapted to move. This arrester consists of a stem-like portion which extends through the housing and has a head 128 at one end thereof to limit the movement of the arrester in one direction. The opposite end of the stem is provided with an enlarged head 129 which is normally maintained in the projected position, represented in Fig. 9, by a coiled expansion spring 130 that surrounds the stem of the arrester and bears at one end 131 against the housing, whereas the opposite end 132 of this spring bears against an enlarged portion 133 of the stem which is received in an opening in the housing and adapted to guide the arrester in its longitudinal movement within the housing. The enlarged head 129 of the arrester is adapted to be interposed in the path of movement of the abutment 84 on the other member of the line locking mechanism when the carriage has moved a predetermined extent from right to left, as determined by the positioning of the adjustable stop 120 and as clearly indicated in Fig. 4 of the drawings. Secured to the underside of the rack 121 by screws 134 is an abutment 135 which projects into the path of the screw stop or abutment 105 and is adapted to coöperate therewith in the movement of the carriage from right to left. The parts are so positioned that just before the end of the line is reached the stop 119 will contact with the stop 120, thereby causing a slight longitudinal movement of the rack bar 121. This movement of the rack bar will cause the abutment 135 to force the upper end of the arm 103 toward the left (looking from the front of the ma-

chine), thereby raising the arm 81 off the stop 94, as represented in dotted lines in Fig. 4, so that the part is moved which constitutes a stop for limiting the movement of the part 37, the dog rocker and the universal bar 70 to normal position. The spring 77 then becomes effective to move the dog rocker and the abutment 84 toward the rear of the machine and away from and out of the path of the arrester and to move the universal bar 75 up close to the key levers as shown in Fig. 5. A slight further movement of the carriage from right to left will bring the enlarged head 129 of the arrester in the path of the abutment 84, as shown in Fig. 4, thus preventing 80 further vibration of the part 37 and the dog rocker connected thereto so that further feed movement of the carriage is prevented and an actuation of the finger keys cannot take place by reason of the fact that the escapement mechanism is locked against movement and consequently the universal bar cannot be depressed from the position shown in Fig. 5 to which it has been elevated. By providing a spring pressed arrester of the 85 character described, I am enabled to avoid the liability of the parts being blocked, should the arrester be brought into contact with the side of the abutment 84 before the abutment can be moved out of the path 90 thereof. Thus for instance, if the end of the arrester should be brought to bear against the side of the abutment 84 before the latter has an opportunity to move out of the path thereof, it will not block the operation of the 95 parts but will merely tend to press the arrester against the tension of its spring 130 and the binding action is insufficient to prevent the abutment 84 from being moved to the proper position away from the arrester or 100 toward the rear of the machine. When it has been moved away from the arrester, the tension of the spring 130 on the latter will automatically interpose the enlarged head 105 110 120 125 130 135 140 145 150 155 160 165 170 175 180 the normal position with the head projected forward. The rear end of the rod 136 is bent upwardly to form an arm 140 (see Fig. 4) which arm is received within a slot in a depending bracket 141 secured to the underside of the stop rod 121 in the usual manner. A longitudinal movement of the rod 136 towards the rear of the machine will cause the stop rod to be turned on its pivot pins 122, thus moving the arrester out of the path of the part 84 carried by the locking element 37; the part 37 being no longer obstructed, it is free to vibrate and the depression of the key levers is permitted so that one or more additional characters may be written to complete the word or sentence or to insert a hyphen.

The actuation of the escapement mechanism affords a step-by-step feed movement of the carriage from right to left, the carriage being propelled in this direction by a spring drum 142 which is connected to the carriage by a band 143 in the usual manner. When the carriage is moved from left to right the feed pinion 108 will be rotated but the escapement wheel 106 is intended to remain fixed against movement at this time. There is, however, a tendency of the pawls (not shown) which are contained within the housing 144 to carry the escapement wheel in a backward direction during the riding of the pawls over the coöperating ratchet wheel and through frictional contact therewith. In order to prevent any backward movement whatever of the escapement wheel 106, I have provided a back stop pawl 145 that has a sleeve 146 projecting therefrom. This sleeve surrounds screw pivot 147 which takes at its lower end in a threaded opening in a bracket 148 and a washer 147^x is interposed between the head of the screw and the sleeve. A coiled spring 149 surrounds this sleeve and is secured thereto at one end 150, whereas the opposite end of this spring is secured at 151 to a lateral extension of the bracket. The pawl 145 is provided with a depending lug 152 which is adapted to abut against the bracket at 152^x as illustrated in Figs. 6 and 8, and to limit the movement of the pawl in one direction. The bracket 148 may be secured by screws 153 to a laterally projecting lug 154 that extends from the plate-like bracket 42. From an examination of Fig. 6, it will be seen that the pawl 145 is adapted to bear against the escapement wheel in a direction at right angles to the plane thereof and that the cam-like portion 155 on the pawl is adapted to be operated upon by the edges 156 of the teeth of the escapement wheel and to deflect the pawl against the tension of its spring 149. As soon, however, as the wheel rotates to a position where one of the radial spaces 157 at the base of the teeth of the escapement wheel is brought opposite to the engaging hook or nose 158, said nose will be forced into the space, thus positively preventing a backward movement of the escapement wheel or a movement in the direction of the arrow in Fig. 6. It will be seen that the pawl by reason of its engagement with the star wheel in a direction at right angles to the plane thereof is maintained at all times in engagement with the star wheel, either frictionally, when the pawl bears against the side of the teeth or in positive engagement in a recess or opening between the teeth thereof, so that there is at all times a tendency to prevent any backward rotation of the escapement wheel during a movement of the carriage from left to right.

In certain characters of typewriting machines in use, considerable difficulty has been occasioned when undue pressure was exerted upon the finger keys in the operation of the machine. In such machines, the dog rocker is usually provided with a stop to limit its forward movement and the downward movement of the universal bar, but the undue pressure referred to resulted in springing the key levers which tended to straighten the bent connecting links or wires between the key levers and type bars and this effected a derangement in the adjustment of the machine. This is especially true where a large number of type bars are employed and the size of the basket is correspondingly increased and there is a greater inclination and the degree of bend of the connecting links between the key levers and type bars. By arranging the universal bar near the front of the machine, or between the finger keys and connecting wires, in accordance with my present invention, I am enabled to overcome the difficulties pointed out above by reducing the objectionable spring in the key levers when the universal bar is arrested by the stop 71 on the dog rocker contacting with the coöperative stop 72, and the resistance of the universal bar at this point tends to lift the connecting links rather than to strain or straighten them, should there be any spring in the key levers. I am therefore enabled to provide an action for the escapement mechanism which is less liable to become deranged or thrown out of adjustment and which is more positive in its nature and accurate in operation than heretofore. By the construction shown and described, I am likewise enabled to mount the feed dog rocker shaft much closer to the top plate of the machine and can therefore provide a shorter dog rocker and much lighter escapement mechanism than was customary heretofore. This will be appreciated from an examination of Fig. 4 of the drawings. It will be understood that by shortening the distance between the rock shaft of the dog rocker and the escapement wheel, I am enabled not only to provide a lighter escapement mechanism, but one which is rigid,

notwithstanding the lightness thereof and which is quicker and more efficient than the heavier escapements with longer dog rockers heretofore employed.

- 5 From the foregoing description it will be understood that when the finger piece 95 is adjusted so that the parts are normally disposed as shown in Fig. 1, the initial movement of the key levers and type bars independently of the dog rocker or escapement mechanism affords an inertia of the former to effect a movement of the latter and that an improved easy "touch" on the finger keys therefore results. It will also be understood that the weight 86 affords an inertia for the lever 82 which is substantially the same as the dog rocker and the movement of this weight in a horizontal direction obviates reaction of the lever by gravitation of the 20 weight and reduces the vibration of the dog rocker to a minimum. Furthermore, the dog rocker spring and the spring 88 being nearly, though not quite of equal strength, the dog rocker when in motion might over- 25 come the spring 88 and the lever 82 would react more quickly, were it not provided with the weight 86 and there would be a possibility of the carriage skipping a space without printing by reason of the spacing or 30 feed dogs being adjusted to engage the teeth of the escapement wheel a short distance that will not admit of any considerable or unusual vibration thereof without effecting a skipping movement of the carriage.
- 35 An adjustment of the sleeve 96 is ordinarily effected in the first instance primarily to regulate the height of the stop 94 when the latter is set in the uppermost position in the sleeve 96, in order to regulate the position of 40 the dog rocker. Incidentally this regulation of the sleeve 96 also regulates in part the position of the universal bar with reference to the key levers. If further regulation of the universal bar is necessary to increase or de- 45 crease the "lead" of the key levers this may be effected by the thumb nuts 20. Thus, it will be seen that the sleeve 96 and thumb nuts 20 or both may be employed as conditions may dictate to determine the extent of 50 "lead" or the extent of lost motion between the key levers and universal bar, whether the stop 94 be set to bring the universal bar and key levers into close proximity as indicated in Fig. 5 or the stop 94 be set to afford a pronounced lost motion as indicated in Fig. 1. These adjustments being once effected it is 55 ordinarily unnecessary to change them. In order to vary the touch of the finger keys within the limits determined by the adjustment of the stop 94 in the sleeve 96, it is merely necessary to raise or lower the stop 94 through the knurled head 95. If, for instance, it be desired to lighten the touch on the machine, it is merely necessary to slightly 60 raise the stop 94, at the same time turning the knurled head and thus permit the pins 100 to be seated within the lowermost set of recesses 101 instead of the upper ones. This lowering movement of the stop 94 is effective to lower the arm 81. From an examination 70 of Fig. 5, it will be understood that a lowering of the arm 81 lowers the arm 36 from the full to the dotted line position shown in that figure and that this movement will cause, through the intermediate link and bell crank 75 connections, a lowering of the universal bar to the dotted line position and that thereafter the movement of the dog rocker and the parts connected thereto such as the universal bar will be limited in one direction, or in 80 their return to normal position by the arm or stop 81 in its lowered position. A depression of the finger key at this time will afford considerable lost motion of the key lever before it comes into contact with the universal 85 bar to move the escapement mechanism, and an easier touch and free initial movement is thereby afforded. Furthermore, it will be observed that the locking element 84, by the 90 movements of the parts just described, is moved from the full line to the dotted line position in Fig. 5 and the feed dogs and the carrier receive a like movement. This movement of the feed dogs however, in no way affects the operation of the escapement 95 mechanism, the construction and relation of the parts being such that it is merely a question of moving the feed dogs transversely of the rack to a greater or less extent depending upon the adjustment of the stop 94, and arm 100 81 and without changing the feed action of the escapement mechanism. In one case the feed dogs in the actuation of the machine, receive a transverse movement from an initial position which corresponds to that indicated 105 by the dotted line position of the part 84 in Fig. 5, and in the other case the feed dogs receive a transverse movement of greater extent and from an initial position that corresponds to the full line position of the part 84 110 in Fig. 5. In other words, an adjustment of the stop 94 causes the universal bar to be taken up and the parts controlled thereby to be moved sooner or later in accordance with the adjustment of the stop thereby bringing 115 about a change in the touch of the finger keys without changing the feed action of the parts. The feed dogs always coöperate to release the carriage at the same time, say, for instance, as soon as the finger of the operator starts to 120 release the key, whether the feed dog carrier has a long or short throw. In the event of the feed dog carrier having a long throw the first part of the movement is inert and does not change the time of let-off of the carriage 125 with relation to the release of the finger key by the operator though the universal bar is taken up sooner and the dog rocker and associated parts are moved further and a heavier touch results.

From the foregoing description it will be understood that the part 84 normally stands in either one of two positions, as indicated in full and dotted lines in Fig. 5, the normal position depending upon the adjustment of the stop 94. When the part 84 normally stands in the full line position the arm 81 is in its highest adjusted position and there is little or no lost motion between the key levers and the universal bar. Adjustment of the thumb nuts 20 determines whether there is to be only a little or there is to be no lost motion whatever between the key levers and universal bar at this time. In practice I prefer to adjust the thumb nuts 20 so that when the part 84 normally stands in the full line position shown in Fig. 5 there will be a slight lost motion between the key levers and universal bar. At this time the screw stop 105 carried by the arm 103 is in the furthest adjusted position towards the left (looking from the front of the machine) and when the parts are in the position described the arrester, or the head 129 thereof, will be interposed in the path of a part 84, during the travel of the carriage from right to left before the abutment 135 reaches contact with the screw stop 105 and there is no necessity for bringing the abutment 135 and stop 105 into play. This is because the adjustment of the parts described normally maintains the arm or part 84 in a position where there is no liability of it interfering with the interpositioning of the arrester in its path and because there is little or no lost motion between the key levers and universal bar and there is therefore no necessity of moving the universal bar up to compensate for the lost motion and thus prevent an appreciable depression of the key levers when the universal bar is locked against movement at the end of a line. When, however, the stop 94 is lowered to change or lighten the touch on the keys it permits a lowering of the arm 81, thereby forcing down the arm 36 which results in dropping the universal bar to the position shown in Fig. 1, thus creating a lost motion between the key levers and universal bar. This same movement of the stop 94 results in bringing the part 84 of the locking element further forward or towards the path of movement of the arrester with the carriage. The lowering of the arm 81 likewise advances the arm 103 so as to bring the stop 105 thereon further toward the right of the machine (looking from the front) and during the movement of the carriage from right to left the abutment 135 will reach contact with the screw stop 105 before the arrester is interposed in the path of the part 84 as indicated in Fig. 2. The contact between the abutment 135 and the screw stop 105 is effective during a further movement of the carriage to rock the bell crank lever, comprising the parts or arms 85, 81 and 103, on its pivots 83, so that the arm 81 is automatically moved up to the dotted line position represented in Fig. 4, thereby moving the universal bar up to the position shown in Fig. 5 to automatically take up the lost motion between the key levers and universal bar. During this movement of the arm 81 the arm 36 follows it up and permits the part 84 to move back toward the rear of the machine, say to the full line position represented in Fig. 5, where it will not obstruct the movement of the arrester and will permit it to be interposed in the path of the part 84, as represented in Fig. 4, so that an attempt to depress the key lever at this time will cause the part 84 to be brought into contact with the head 129 of the arrester, thereby preventing a movement of the feed dog rocker and thus preventing a depression of the key levers by locking the universal bar against movement in an elevated position where little or no appreciable movement of the key levers can be effected.

From the foregoing description it will be understood that when the stop 94 is elevated, the arrester will be interposed in the path of the part 84 without actuating the mechanism automatically through the contact of the abutment 135 with the screw stop 105 and that when the part 84 is normally in the dotted line position the abutment 135 automatically bears upon the screw stop 105 during the movement of the carriage from right to left and moves the part 84 out of the path of the advancing arrester so as to permit the head 129 thereof to be interposed in the path of the part 84 and also automatically moves the universal bar up to take up the lost motion, and that this variation in the action of the parts is rendered necessary by the adjustment of the part 94 which effects a change in the touch on the finger keys, because in one case the part 84 is normally clear of the arrester and in the other case the part 84 extends closer to or in the path of movement of the arrester and in one case there is a material lost motion between the key levers and universal bar and in another case there is no lost motion or no material lost motion and when there is lost motion it is desirable to take it up in the line locking operation to prevent an appreciable key depression and a possibility of printing operations being effected through an attempted actuation of the keys at this time.

From the foregoing description it will be seen that the part 81 constitutes a stop for the universal bar to determine the normal position thereof and through which the normal position of the universal bar may be varied; that said stop is automatically controlled by the line lock mechanism; that the position of the stop may also be controlled by hand through the finger piece 95; that the automatic operation of the stop 81 con-

stitutes means for automatically taking up lost motion between the keys and the universal bar as an end of a line is approached; that means are provided for locking said universal bar against movement after said lost motion is taken up; that the stop 81 under certain circumstances arrests the universal bar (as shown in Fig. 1) before it reaches the end of its full return motion; 10 that there are operative connections between said stop and the line lock mechanism to move said stop before the line locking takes place; that the stop 81 is controlled by the line lock stop 120, and that the automatic 15 movement of the stop 81 is effected by the movement of the carriage.

While I have illustrated my invention in its application to a No. 6 Remington machine, it should be understood that the invention may be applied to other characters 20 of machines, and that the various features of the invention may be applied separately or combined and that various changes may be made without departing from the spirit 25 of my invention.

Having described my invention what I claim as new and desire to secure by Letters Patent, is:—

1. In a typewriting machine, the combination of a carriage, escapement mechanism therefor, said escapement mechanism including a dog rocker, adjusting means for affording a variable throw to said dog rocker, a universal bar, the throw of the universal bar 35 varying with the variation in the throw of the dog rocker and without changing the feed action of the escapement mechanism, line locking means, and means for automatically moving said adjusting means.

2. In a typewriting machine, the combination of a carriage, escapement mechanism therefor, adjusting means for affording a variable throw to one member of said escapement mechanism, a key actuated universal bar, the throw of which varies with 45 that of member having the variable throw and without changing the feed action of the escapement mechanism, line lock means, and means for automatically moving said adjusting means.

3. In a typewriting machine, the combination of a platen, a power driven carriage carrying said platen, escapement mechanism for affording a step-by-step movement of the carriage for a given extent in the direction of 55 its travel at each printing operation, type bars, key levers, connecting links intermediate of the type bars and key levers, a universal bar located between the connecting links 60 and the finger keys of the key levers, operative connections between said universal bar and escapement mechanism, and automatically actuated means for arresting said universal bar before undue strain is put on said links.

4. The combination of a carriage, escapement mechanism therefor, key levers, a universal bar extending beneath said key levers at the forward portions thereof, a rock shaft located at the front portion of the machine, 70 means for connecting said rock shaft to the universal bar, and means for transmitting movement from said rock shaft to the escapement mechanism at the rear of the machine.

5. The combination of a carriage, a feed rack, therefor, feed dogs coöperating with said feed rack, a dog rocker, key levers, a universal bar extending beneath said key levers at the forward portions thereof, and intermediate bell crank and link connections between the universal bar at the forward portions of the key levers and the dog rocker at the rear of the machine.

6. The combination of a carriage, a feed 85 rack therefor, feed dogs which coöperate with said feed rack, a dog rocker which carries said feed dogs, key levers, a universal bar extending beneath said key levers at the forward portions thereof, a rock shaft at the forward portion of the machine, connections between said rock shaft and universal bar, and intermediate bell crank and link connections between the rock shaft and dog rocker.

7. The combination of a carriage, escapement mechanism therefor, key levers, a universal bar extending beneath said key levers at the forward portions thereof, means for transmitting movement from said universal bar at the forward portions of the key levers 95 to the escapement mechanism at the rear of the machine, and line lock mechanism which coöperates with the escapement mechanism to lock it against movement when an end of 100 a line is reached.

8. The combination of a power driven carriage, a feed rack carried thereby, a feed pinion with which said rack meshes, an escapement wheel operatively connected to said feed pinion, feed dogs which coöperate 110 with said escapement wheel, a dog rocker which carries said feed dogs, key levers, a universal bar extending beneath said key levers at the forward portions thereof, a rock shaft which extends from side to side of the 115 machine at the forward portion thereof, crank arms projecting from said rock shaft, a rearwardly extending link connected to one of said crank arms, a bell crank connected to the rear end of said link, and a link connection between said bell crank and dog rocker.

9. In a typewriting machine and line lock mechanism, the combination of a carriage, escapement mechanism therefor, a spring pressed arrester, and means for automatically 125 interposing said arrester in the path of a member of the escapement mechanism when an end of a line is reached.

10. In a typewriting machine and line lock mechanism, the combination of a carriage, a 130

feed rack therefor, feed dogs which coöperate with said feed rack, an arrester, a spring which normally maintains said arrester in the projected position, and means controlled 5 by the movement of the carriage for interposing the arrester in the path of a part which moves with the feed dogs in their movement transversely of the feed rack.

11. In a typewriting machine and line lock 10 mechanism, the combination of a power driven carriage, a feed rack therefor, feed dogs which coöperate with said feed rack, a dog rocker which carries said feed dogs, an arm adjustably connected to the dog rocker, 15 a stop rod which has a limited movement in the direction of the travel of the carriage, an arrester which is carried by said stop rod, a spring which normally maintains said arrester in the projected position, and an abutment carried by the carriage for moving said stop rod to interpose the arrester in the path 20 of said adjustable arm.

12. In a typewriting machine, the combination of a carriage, escapement mechanism 25 therefor, key actuated devices, a universal bar which is actuated by said key actuated devices, and means for adjusting the universal bar relatively to the key actuated devices, the parts including means whereby the 30 said adjustment of the universal bar is ineffective to alter the action of the escapement mechanism in the operation of the machine.

13. In a typewriting machine, the combination of a power driven carriage, escapement mechanism therefor, key levers, a universal bar which extends beneath and is actuated by said key levers, and hand operated means for adjusting the universal bar at will relatively to the key levers, the parts 40 including means whereby the said adjustment of the universal bar is ineffective to alter the action of the escapement mechanism in the operation of the machine, and so that the universal bar may be taken up by 45 the key levers sooner or later in accordance with said adjustment and the touch of the key levers accordingly altered.

14. In a typewriting machine, the combination of a carriage, escapement mechanism 50 therefor, key levers, a universal bar which extends transversely of said key levers at the forward portions thereof and which is connected to the escapement mechanism, and hand operated means for adjusting the 55 universal bar at will relatively to the key levers, the parts including means whereby the said adjustment of the universal bar is ineffective to alter the action of the escapement mechanism and so that the universal bar 60 may be taken up by the key levers sooner or later in accordance with said adjustment and the touch of the key levers accordingly altered.

15. In a typewriting machine, the combination of a power driven carriage, a feed 65

rack therefor, feed dogs which coöperate with said rack, a dog rocker, key levers, a universal bar which extends transversely of said key levers at the forward portions thereof, and which is connected to the dog rocker, 70 and hand operated means for adjusting the universal bar at will relatively to the key levers, the parts including means whereby the said adjustment of the universal bar is ineffective to alter the action of the escapement mechanism and so that the universal bar may be taken up by the key levers sooner or later in accordance with said escapement 75 mechanism and the touch of the key levers accordingly altered. 80

16. In a typewriting machine, the combination of a power driven carriage, a feed rack therefor, feed dogs which coöperate with said rack, a dog rocker, key levers, a universal bar which extends transversely of 85 said key levers at the forward portions thereof, a rock shaft which extends cross-wise of the machine, crank and link connections between said universal bar and rock shaft and between the rock shaft and dog rocker, and hand operated means for adjusting the universal bar at will relatively to the key levers and so that the universal bar may be taken up by the key levers sooner or later in accordance with said adjustment and the touch 90 of the key levers accordingly altered.

17. The combination of a carriage, escapement mechanism therefor, key levers, a universal bar extending beneath said key levers at the forward portions thereof, means for 100 transmitting movement from said universal bar at the forward portions of the key levers to the escapement mechanism at the rear of the machine, line lock mechanism which cooperates with the escapement mechanism to 105 lock it against movement when an end of a line is reached, and hand operated means for adjusting the universal bar relatively to the key levers so that the universal bar may be taken up by the key levers sooner or later in 110 accordance with said adjustment and the touch of the key levers accordingly altered.

18. The combination of a power driven carriage, a feed rack carried thereby, a feed pinion with which said rack meshes, an escapement wheel operatively connected to said feed pinion, feed dogs which coöperate with said escapement wheel, a dog rocker which carries said feed dogs, key levers, a universal bar extending beneath said key 120 levers at the forward portions thereof, a rock shaft which extends from side to side of the machine at the forward portion thereof, crank arms projecting from said rock shaft, a rearwardly extending link connected to one of said crank arms, a bell crank connected to the rear end of said link, and a link connection between said bell crank and dog rocker, and hand operated 125 means for adjusting the universal bar rela- 130

tively to the key levers so that the universal bar may be taken up by the key levers sooner or later in accordance with said adjustment and the touch of the key levers accordingly 5 altered.

19. In a typewriting machine and line lock mechanism, the combination of a power driven carriage, a feed rack therefor, feed dogs which coöperate with said feed rack, a 10 dog rocker which carries said feed dogs, an arm adjustably connected to the dog rocker, a stop rod which has a limited movement in the direction of the travel of the carriage, an arrester which is carried by said stop rod, a 15 spring which normally maintains said arrester in the projected position, and an abutment carried by the carriage for moving said stop rod to interpose the arrester in the path of said adjustable arm, key levers, a universal 20 bar which is located beneath said key levers at the forward portions thereof and which is operatively connected to the dog rocker and hand operated means for adjusting said universal bar relatively to the key levers so that 25 the universal bar may be taken up by the key levers sooner or later in accordance with said adjustment and the touch of the key levers accordingly altered.

20. In a typewriting machine, the combination of a carriage, a feed rack therefor, feed dogs which coöperate with said feed rack, a dog rocker, an abutment or stop which limits the movement of the dog rocker in one direction, means controlled by the movement of 30 the carriage for moving said abutment, and line locking instrumentalities.

21. In a typewriting machine, the combination of a carriage, a feed rack therefor, feed dogs which coöperate with said feed rack, a 40 dog rocker, a spring pressed abutment or stop which is independent of and limits the movement of the dog rocker in one direction, means controlled by the movement of the carriage for moving said abutment, independent 45 hand operated means for adjusting said abutment, and line locking instrumentalities.

22. In a typewriting machine, the combination of a carriage, a feed rack therefor, feed 50 dogs which coöperate with said feed rack, a spring pressed dog rocker, an independently spring pressed abutment or stop which is independent of and limits the movement of the dog rocker in one direction, and the 55 spring tension on which is greater than that on the dog rocker, means controlled by the movement of the carriage for moving said abutment against its spring tension, independent hand operated means for adjusting 60 said abutment, and line locking instrumentalities.

23. In a typewriting machine, the combination of a carriage, a feed rack therefor, feed dogs which coöperate with said rack, a dog 65 rocker for said feed dogs, an abutment or

stop which limits the movement of the dog rocker in one direction, key levers, a universal bar which is actuated by said key levers and is connected to the dog rocker, and means for adjusting said abutment to effect 70 an adjustment of the universal bar relatively to the key levers, so as to vary the touch without altering the feed of the escapement mechanism.

24. In a typewriting machine, the combination of a carriage, a feed rack therefor, feed dogs which coöperate with said rack, a dog rocker for said feed dogs, a spring pressed abutment or stop which is independent of and limits the movement of the dog rocker in 80 one direction, means controlled by the movement of the carriage for moving said abutment, line locking instrumentalities, key levers, a universal bar which is actuated by 85 said key levers and is connected to the dog rocker, and means for adjusting said abutment to effect an adjustment of the universal bar relatively to the key levers, so as to vary the touch without altering the feed of the escapement mechanism. 90

25. In a typewriting machine, the combination of a carriage, a feed rack therefor, feed dogs which coöperate with said rack, a spring pressed dog rocker for said feed dogs, an independently spring pressed abutment or stop 95 which is independent of and limits the movement of the dog rocker in one direction, and the spring tension of which is greater than that on the dog rocker, means controlled by the movement of the carriage for moving said 100 abutment against its spring tension, line locking instrumentalities, key levers, a universal bar which is actuated by said key levers, and is connected to the dog rocker, and hand operated means for adjusting said abutment to 105 any one of several positions to effect an adjustment of the universal bar relatively to the key levers, so as to vary the touch without altering the feed of the escapement mechanism. 110

26. In a typewriting machine, the combination of a carriage, a feed rack therefor, feed dogs which coöperate with said rack, key levers, a universal bar which is actuated by the key levers, and hand operated means 115 for simultaneously changing the normal positions of the feed dogs and universal bar so as to alter the touch without affecting the feed movement of the carriage.

27. In a typewriting machine, the combination of a carriage, escapement mechanism, line locking instrumentalities, one member of which moves with a part of the escapement mechanism and is adapted to be blocked at a predetermined point in the travel of the carriage, means for adjusting said member relatively to the part of the escapement mechanism with which it moves, key levers and intermediate connections between the key levers and said member. 120 125 130

28. In a typewriting machine, the combination of a carriage, a feed rack therefor, a rock shaft, a feed dog carrier fixed to said shaft, line locking instrumentalities one member of which is loosely mounted on said shaft, means for adjustably securing said member to the dog rocker, a link which is connected to said member, key levers, a universal bar extending beneath said key levers, and intermediate connections between the universal bar and said link.

29. In a typewriting machine, the combination of a carriage, a feed rack therefor, feed dogs, a dog carrier, a spring pressed bell crank lever which limits the movement of said dog carrier, and a hand-operated spring-pressed stop which is adapted to be set in a plurality of positions and to limit the movement of the bell crank lever.

20. 30. In a typewriting machine, the combination of a carriage, a feed rack therefor, feed dogs, a dog carrier, a spring pressed bell crank lever which limits the movement of said dog carrier, a hand operated spring-pressed stop which is adapted to be set in a plurality of positions and to limit the movement of the bell crank lever, an adjustable abutment carried by said bell crank lever, a coöperating abutment on the carriage, and line locking instrumentalities.

31. In a typewriting machine, the combination of a carriage, a feed rack therefor, feed dogs, a spring restored dog carrier, a spring pressed bell crank lever which limits the movement of said dog carrier, and the tension of the spring of which is greater than that of the spring for the dog carrier, means for adjusting the tension of the spring of said bell crank lever, a hand-operated spring-pressed stop which is adapted to be set in a plurality of positions and to limit the movement of the bell crank lever, an adjustable screw abutment carried by said bell crank lever, an adjustable coöperating abutment on the carriage, line locking instrumentalities, key levers, a universal bar actuated by said key levers, and operative connections between the bell crank lever and the universal bar.

50. 32. In a typewriting machine, and line lock mechanism, the combination of a carriage, line locking instrumentalities, and means for automatically moving one member of said locking instrumentalities away from the other during the travel of the carriage in order to insure the interpositioning of one member of said locking instrumentalities in the path of the other before the locking movement takes place.

60. 33. In a typewriting machine and line lock mechanism, the combination of a carriage, line locking instrumentalities, which include a spring pressed arrester, and means for automatically moving a member of said locking instrumentalities away from the

arrester during the travel of the carriage in order to insure the interpositioning of said arrester in the path of a member of said locking instrumentalities before the locking movement takes place.

70

34. In a typewriting machine, the combination of a carriage, a feed rack therefor, feed dogs, a rocker which carries said feed dog, line locking instrumentalities one member of which is adjustably connected to the dog rocker, and the other member of which consists of spring pressed arrester, means for interposing said arrester in the path of the member which is connected to the dog rocker and means for automatically moving the said last mentioned member away from the arrester during the travel of the carriage to assure a subsequent interpositioning of the arrester.

75

35. In a typewriting machine, the combination of a carriage, a feed rack therefor, feed dogs, a rocker which carries said feed dog, a line locking member which is adjustably connected to the dog rocker, a stop bar that is adapted to move in the direction of the travel of the carriage, a spring pressed arrester which coöperates with the said locking member to arrest the movement of the feed dogs, means for moving said stop bar at a predetermined point in the travel of the carriage to interpose said arrester in the path of the locking member, and means for automatically moving the said locking member away from the arrester during the travel of the carriage to assure a subsequent interpositioning of the arrester.

95

36. In a typewriting machine, and line lock mechanism, the combination of a carriage, line locking instrumentalities, means for automatically moving one member of said locking instrumentalities away from the other during the travel of the carriage in order to insure the interpositioning of one member of said locking instrumentalities in the path of the other before the locking movement takes place, and hand operated means for releasing said line locking instrumentalities.

100

37. In a typewriting machine and line lock mechanism, the combination of a carriage, escapement mechanism therefor, a spring pressed arrester, means for automatically interposing said arrester in the path of a member of the escapement mechanism when an end of a line is reached, and hand operated means for moving said arrester out of the path of said member of the escapement mechanism.

110

38. In a typewriting machine and line lock mechanism, the combination of a carriage, line locking instrumentalities, which include a spring pressed arrester, means for automatically moving a member of said locking instrumentalities away from the arrester during the travel of the carriage in order to

120

125

130

insure the interpositioning of said arrester in the path of a member of said locking instrumentalities before the locking movement takes place, and hand operated means for moving the arrester out of the path of the said member of the line locking instrumentalities to permit one or more characters to be written after the parts have been locked.

39. In a typewriting machine, the combination of a carriage, feed rack therefor, feed dogs, a rocker which carries said feed dog, a line locking member which is adjustably connected to the dog rocker, a stop bar that is adapted to move in the direction of the travel of the carriage, a spring pressed arrester, which coöperates with the said locking member to arrest the movement of the feed dogs, means for moving said stop bar at a predetermined point in the travel of the carriage to interpose said arrester in the path of the locking member, means for automatically moving the said locking member away from the arrester during the travel of the carriage to assure a subsequent interpositioning of the arrester, and hand operated means for rocking said stop bar to move the arrester out of the path of the line locking member connected to the dog rocker, whereby one or more characters may be written after the line locking mechanism has been actuated to lock the parts.

40. In a typewriting machine, the combination of a carriage, an escapement wheel operatively connected to said carriage, a dog rocker, feed dogs mounted on said dog rocker and which coöperate with said escapement wheel, and a pawl mounted independently of the dog rocker and which engages the said escapement wheel laterally of the plane thereof and prevents a reverse or backward movement of the wheel during the movement of the carriage from left to right.

41. In a typewriting machine, the combination of a carriage, escapement mechanism therefor, type bars, finger keys, adjustable means for affording an initial movement of the finger keys independently of the escapement mechanism, and automatically actuated line block mechanism including a member operatively connected to the escapement mechanism, the construction and arrangement being such that an adjustment of said adjustable means affects said member.

42. In a typewriting machine, the combination of a carriage, carriage feed mechanism, printing keys, a lost motion connection between said printing keys and carriage feed mechanism, line lock mechanism, and means for automatically dispensing with more or less of such lost motion before the line lock becomes effective.

43. In a typewriting machine, the combination of a carriage, carriage feed mechanism, printing keys, a lost motion connection between said printing keys and carriage feed

mechanism, line lock mechanism, and means controlled by the movement of the carriage for automatically preventing more or less of such lost motion between said printing keys and carriage feed mechanism.

44. In a typewriting machine, the combination of a carriage, carriage feed mechanism, printing keys, hand-actuated means operable at will to provide a lost motion between said printing keys and carriage mechanism, line lock mechanism, and means for automatically dispensing with more or less of the lost motion before the line lock becomes effective.

45. In a typewriting machine, the combination of a carriage, carriage feed mechanism, printing keys, a lost motion connection between said printing keys and carriage feed mechanism, line lock mechanism, and means controlled by said line lock mechanism for automatically taking up lost motion before said line lock mechanism becomes effective to lock the printing keys out of operation.

46. In a typewriting machine, the combination of a carriage, carriage feed mechanism including a universal bar, finger keys for actuating said universal bar, lost motion connection between said finger keys and universal bar, line lock mechanism, and automatic means for taking up lost motion between the finger keys and universal bar before the line lock mechanism becomes effective to lock the machine out of operation.

47. In a typewriting machine, the combination of a carriage, carriage feed mechanism including a universal bar, finger keys for actuating said universal bar, lost motion connection between said finger keys and universal bar, line lock mechanism, and means controlled by the carriage feed movement for automatically taking up lost motion between the finger keys and universal bar before the line lock mechanism becomes effective to lock the machine out of operation.

48. In a typewriting machine, the combination of a carriage, carriage feed mechanism including a universal bar, finger keys for actuating said universal bar, lost motion connection between said finger keys and universal bar, line lock mechanism, and means controlled by the line lock mechanism for automatically taking up lost motion between the finger keys and universal bar before the line lock mechanism becomes effective to lock the machine out of operation.

49. In a typewriting machine, the combination with the carriage and the series of keys, of a universal bar, a stop for arresting said universal bar at different positions, and a line lock mechanism arranged to control said stop in order to vary the position of arrest of the universal bar and to lock it.

50. In a typewriting machine, the combination with the carriage and the series of keys, of a universal bar operated by said

keys, there being lost motion between said keys and said universal bar, and means controlled by said carriage at the end of a line for taking up lost motion between said keys 5 and said universal bar and locking said universal bar.

51. In a typewriting machine, the combination with the carriage, of a series of keys, a universal bar, an escapement mechanism operated by said universal bar, means adjustable to vary the point in the motion of a key at which said key begins to actuate said escapement mechanism, and a line lock mechanism controlled by said carriage and including means operative to lock said universal bar at a given point irrespective of the adjustment of said adjustable means.

52. In a typewriting machine, the combination of a series of keys, an escapement mechanism, a universal bar actuated by said keys and operating said escapement mechanism, an adjustable stop for arresting said universal bar at different points in its return motion, automatic means for moving said stop to enable said universal bar to return to its extreme position, and a line lock means coöperative with said universal bar to lock it in its extreme return position.

53. In a typewriting machine, the combination with keys and type mechanism operated thereby, of a universal bar, an adjustable stop for said universal bar, and a line lock mechanism operatively connected to said stop to move it in order to vary the normal position of the universal bar.

54. In a typewriting machine, the combination of a series of keys, a universal bar, a movable stop for arresting said universal bar before it reaches the end of its full return motion and to determine a working position of said bar, line lock mechanism coacting with said universal bar, and connections whereby said line lock mechanism moves said stop to afford a movement of the universal bar out

of working position to the end of its full 45 return motion before the fine locking takes place.

55. In a typewriting machine, the combination with the keys and type mechanism and a universal bar actuated by said keys, of 50 stop mechanism for arresting the universal bar at a point short of its extreme return position, a line lock mechanism operable only when said universal bar is in said extreme return position, and means whereby said line 55 lock mechanism, in its initial motion, throws said stop mechanism out of its arresting position.

56. In a typewriting machine, the combination of a line stop, a universal bar, and a 60 stop for arresting said universal bar at its return to normal position, the latter stop being controlled by said line stop.

57. In a typewriting machine, the combination with the universal bar, of a stop for 65 arresting said universal bar at its return to normal position, hand actuated means for adjusting said stop, and a line lock device comprising means for automatically moving said stop.

58. In a typewriting machine, the combination of a line stop, a universal bar, and a 70 stop normally in position for arresting the universal bar, the latter stop being controlled by the line stop.

59. In a typewriting machine, the combination of a universal bar, a stop normally in position for limiting the movement of the universal bar, hand actuated means for adjusting said stop, and a line lock device comprising means for automatically moving said stop.
